CAP FOR AEROSOL BOMB

Robert W. Svendsen, Maywood, Ill.

Application July 13, 1950, Serial No. 173,653

7 Claims. (Cl. 299—95)

1

This invention relates to a cap for an aerosol bomb, and particularly is concerned with a cover member for the type of bomb formed as a canister having an annular rim or lip.

Many of the aerosol bombs being sold today are economically made from ordinary cannisters, cylindrical in shape, and having concave ends to enable the bomb to withstand the high internal pressure thereof. The concave ends and the cylindrical wall are formed of relatively thin gauge metal, and each of the ends is crimped in position, forming thereby an annular ridge or lip. One end is provided with a valve biased to a closed position, but adapted to be moved to open position by the user to enable the material in the bomb to discharge through a fine spray jet provided in the valve housing. The valve is operated by means of a dome-shaped flexible diaphragm through which the valve stem may be pressed, and which, by reason of being sealed upon the end of the valve housing, prevents leakage of pressure within the bomb.

Such aerosol bombs are used for dispensing insecticides, wax, deodorizers, paints, and many other liquid materials which can be dissolved in low boiling point spray vehicles. The valve housing and valve button are usually mounted in the center of the top pressure end, and the concavity of the end is such that the housing and button are both below the lip of the bomb. This protects the valve from injury, prevents danger of explosion caused by valve head breakage, and further enables the bombs more easily to be stored.

Heretofore it has been customary to furnish such bombs with a cap completely covering the valve end of the bomb, such cap having flanged edges removably engaged over the bomb lip. Such cap was in the form of a planar disc arranged over the end, and in most cases, an outwardly convex projection was provided in the center thereof to clear the valve button. In some cases, a nesting flange was provided.

In using the type of bomb above described, it was necessary to remove the cap to uncover the valve button. The cap, therefore had to be fairly easy to remove, and hence was readily lost, or misplaced. My invention has as an object the provision of a novel cap which need not be removed from the bomb to enable the bomb to be used, and hence may be relatively securely attached thereto.

An important disadvantage of the aerosol bomb above described is that the valve button is quite small. The valve biasing means must render the

2

valve leak-proof and hence it requires relatively strong downward pressure by the tip of the finger upon the valve button to overcome the force exerted by the biasing means, to dispense the material from the bomb. The engagement of a small area of the finger tip by the valve button is annoying, and in case the button is held down for more than a few seconds, it becomes painful. A principal object of the invention is to provide a protective cap which serves to enable a broader area of the finger tip to be used in operating the aerosol bomb.

Another object of the invention is to provide a cap for an aerosol bomb which serves as a valve operating pressure distribution plate, but which cannot be operated unless the cap is arranged to permit the jet freely to spray the material.

In connection with the last mentioned object, it very often occurs that persons not familiar with the operation of aerosol bombs will press the valve button when the jet is pointed in the wrong direction. The person is likely to soil his clothing, or cause the material to fly into his face. Accordingly, it is another object of my invention to provide a cap constructed in such a manner that only a small segment of the cap is open, it being impossible to operate the valve unless the segment is aligned with the jet, whereby the user must turn the cap to operative position before he can spray the material. Under such circumstances the opening of the cap indicates the proper direction to point the bomb during use, and in addition, indicia may be applied to the cap, in the form of an arrow, for example, to point out such direction when the segment shaped opening is properly aligned with the jet.

Another object of the invention is to provide a cap of the character described which has an opening through which the jet is adapted to direct the spray of material, but which will prevent the valve from being operated until the jet and opening are properly aligned.

Another object of the invention is to provide a cap having means protruding downwardly therefrom and which limits the downward movement of the cap by engaging against a part of the valve housing, but which permits downward movement of the cap when the jet and opening of the cap are properly aligned.

With the foregoing and other objects in view which will appear as the description proceeds, the invention consists of certain novel features of construction, arrangement and a combination of parts hereinafter fully described, illustrated in the accompanying drawings, and particularly

pointed out in the appended claims, it being understood that various changes in the form, proportion, size and minor details of the structure may be made without departing from the spirit or sacrificing any of the advantages of the invention.

For the purpose of facilitating an understanding of this invention, there is illustrated in the accompanying drawings a preferred embodiment thereof, from an inspection of which, when considered in connection with the following description, this invention, its mode of construction, assembly and operation, and many of its advantages should be readily understood and appreciated.

Referring to the drawings in which the same characters of reference are employed to indicate corresponding or similar parts throughout the several figures of the drawings:

Fig. 1 is a top plan view of an aerosol bomb having a cap thereon, which cap is constructed in accordance with my invention, the cap being arranged so that the bomb may be operated for spraying.

Fig. 2 is a fragmentary sectional view taken along the line 2—2 of Fig. 1 and in the indicated direction.

Figs. 3 and 4 are views similar to Figs. 1 and 2 except that in this case the cap has been arranged so that the bomb cannot be operated.

Fig. 5 is an enlarged perspective view of the cap of my invention.

Fig. 6 is a sectional view taken through the cap alone along the line 6—6 of Fig. 1 and in the indicated direction.

Referring now to the illustrated figures, the invention is intended to be associated with a type of aerosol bomb which is in common use today. Said bomb, designated generally 10 consists of an elongate cylindrical cannister having concaved ends. Only the top of the bomb is shown in the figures since the bottom is merely provided with an imperforate concave end of the type which will be described in connection with the top of the bomb. The cannister is formed of a continuous cylindrical wall of thin gauge metal, treated to resist corrosion in any well-known manner. At its upper end the cylindrical wall is covered and tightly sealed by a concave end member 12 whose circumferential edges are interfolded with the circumferential edges of the cylindrical wall 11 to form an annular, protruding ridge or lip 13. The bottom end (not shown) is also provided with a sealed concave member to render the bomb 10 air tight. The bomb is constructed in the manner described in order to withstand relatively high internal gas pressure without bursting.

The center of the end 12 is provided with a valve housing 14 which is generally of cylindrical formation, and which has a shank 15 soldered to the upturned seat 16 of the end 12. The upper edge surface 17 of the valve housing 14 is in the form of a flat ring having a radially extending projection 18 to one side thereof. The projection 18 is the top surface of a nozzle 19 integrally formed with the valve housing 14. The nozzle 19 has a jet 20 which points in such a direction as to spray the material in the manner shown in Fig. 2 at 21. The material is forced from the interior of the bomb 10 through the tube 22, past the valve (not shown) and out of the jet 20.

The valve housing 14 contains a valve mechanism which is not shown herein, but which may be of any suitable and well-known construction. Same forms no part of the invention, but it

should be pointed out that same is biased to a closed position, probably by a very strong spring in order to prevent leakage of the high pressure vapor within the bomb. To overcome this bias there are provided means for pressing the valve against the bias force to open the same. The construction illustrated has some suitable valve mechanism for accomplishing this purpose which has not been illustrated to render the explanation simple. Suffice it to say that in order for the material to be dispensed it is necessary to press downward with the finger upon a valve button 22. This will open the valve, and, when released, will permit the biasing means to close the valve. In the embodiment illustrated the valve button consists of a rubber, dome-shaped diaphragm which rises out of the center of the annular upper edge surface 17 of the valve housing 14. The valve operating mechanism can be pushed through the diaphragm without disturbing the substantially gas-tight seal.

It will be noted that the housing 14 is secured to the end member 12 in such a manner that the surface 17 is below the end of the bomb 10 as defined by the lip 13. The valve button 22 is also preferably below the edge of the lip 13 in order to prevent accidental opening of the valve. This construction makes for less likelihood of damage to the valve housing.

The bomb as thus far described is not intended to be claimed herein, since same is in widespread use at this time. My invention is especially applicable to the type of bomb described, principally because such a bomb is provided with means for enabling a cap to be secured thereto, and means cooperating with my new cap to prevent the button from being pressed unless the cap is properly aligned. The first means consists of the annular lip 13 which can be engaged by the flange of my cap. The second mentioned means consists of the radial projection 18 of the surface 17 which is intended to be engaged by a part of my cap during all positions of my cap but the one where the valve can be operated.

My new cap is designated generally by the character 30 and is best illustrated per se in Figs. 5 and 6. Same consists of a planar disc 31 having the major portion upset, giving rise to a seating flange 32 by means of which a plurality of bombs having such caps may nest one on top of the other. The edge of the cap is provided with a depending flange 33 which may be slightly curved inwardly as best shown at 34 in Fig. 6. The flange 33 is intended to engage over the lip 13 in a relatively snug fit, so that same can easily be snapped in position, but will not readily be removed. The inward curve 34 promotes such an attachment. The cap is shown in position in Figs. 1 to 4 inclusive, and it will be obvious that the cap is capable of being rotated upon the end of the bomb 10.

As shown clearly in Fig. 5, a segment of about 90° is cut away from the cap, giving rise to the triangular opening 35 through which the material from the bomb 10 is intended to be sprayed. When the cap is in place, the apex 36 of the opening 35 cuts across a small chord of the surface 17, and, when aligned with the projection 18 as shown in Figs. 1 and 2, gives free access for spray 21 from the jet 20 to the atmosphere. Since the disc 31 is made of relatively thin gauge material, unless prevented from doing so, the center 37 thereof may be pressed downward because of flexibility thereof. This permits the finger of the user to apply pressure over a large

area, while the pressure is concentrated on the bottom of the cap against the button 22. Pressure of the finger directly upon the button is annoying and may be painful in the case of dispensing wax or paint which requires the valve to be open for more than just a few seconds. The flexible nature of the disc 31 thus provides a valve operating pressure distributing plate functioning to enable the button 22 to be pressed without pain or discomfort. I prefer the use of means to prevent the center 37 of the cap 30 from being depressed unless the nozzle 19 is aligned with the center of the opening 35 which I will presently describe. However, in case such means are not provided, indicia 39 may be placed upon the end member 12 pointing out what the position of the cap 30 must be before the center is pressed. Such position is achieved by the user merely by twisting the cap 30.

The means above referred to, for preventing depressing of the center 37 of the cap 30 unless same is properly aligned consists of a C-shaped projection 41 on the bottom of the disc 31 and concentric thereof. The projection is arranged about the imperforate portion of the disc 31 and is preferably formed by a simple stamping operation which gives rise to the groove 42 in the top of the cap 30. The projection may be a strip of metal soldered in place, or may be a projection integrally formed with the cap 30, such as for example, in case the cap is molded from plastic. The radius of the projection 41 is slightly greater than the radius of the outside edge of the annular surface 17. The projection radius is less, however, than the distance from the center of the ring 17 to the outermost extent of the surface 18, so that the projection 41 will engage the surface 18 of the nozzle 19 at all positions of the cap upon the bomb 10 except that position shown in Figs. 1 and 2 where the jet 20 is unobstructed. The projection 41 is preferably of such thickness as to prevent the bottom of the center 37 from engaging the top of the valve button 22 when the cap 30 is in the position shown in Figs. 3 and 4.

When the bomb is not being used, the cap is arranged as shown in Figs. 3 and 4. This protects the valve housing 14, prevents the button 22 from being pressed, and permits the cans to be stacked by nesting. If it is desired to use the bomb, the cap 30 is twisted to the position shown in Figs. 1 and 2, the nozzle 19 being free, and the jet 20 being pointed as desired. Indicia 45 may be placed on the cap 10 to show the proper direction. The center 37 of the can is pressed with the finger, and the projection 41 clears the annular surface 17 permitting the disc 31 to be deformed to the position shown in broken lines. This presses the button 22, and causes emission of a cloud of spray 21.

The cap 30 may be sold separately from the bomb 10 or may be attached to the bomb by the manufacturer. The construction thereof is such that the bomb is easier to use and more convenient to handle. Furthermore it is rendered safe during storage and non-use periods.

It is believed that this invention, its mode of construction and assembly, and many of its advantages should be readily understood from the foregoing without further description, and it should also be manifest that while a preferred embodiment of the invention has been shown and described for illustrative purposes, the specific details are nevertheless capable of wide vari-

ation within the purview of this invention as defined in the appended claims.

What is claimed and desired to be secured by Letters Patent of the United States is:

- 5 1. A cap for an aerosol bomb of the character described and which includes a centrally arranged valve button, spray nozzle, and a jet in the nozzle, which comprises means for frictionally engaging the cap against the end of the bomb in a manner to enable manual rotation of the cap by twisting the same, an opening in the cap through which the jet can spray, said cap being deformable so that the center thereof can be pressed against the button, the cap being adapted to be turned to a position where the opening is aligned with the jet, and means preventing the center of the can from being pressed against the button unless the opening is aligned with said jet.
- 10 2. A cap for an aerosol bomb of the character described and which includes a centrally arranged valve housing having an annular end and a protruding valve button in the center of the end, and a nozzle defined by radial projection of said end with a jet in the nozzle, said bomb having an end lip; which comprises a deformable disc having depending flanges adapted frictionally to engage over the lip to permit manual twisting of the cap, an opening in the disc through which the jet can emit spray, the disc adapted to be pressed in its center to engage against and depress the valve button, the opening adapted to be aligned with the spray jet, and means preventing the center of the disc from being pressed against the button unless the opening is aligned with said jet.
- 15 3. A cap for an aerosol bomb of the character described and which includes a centrally arranged valve housing having an annular end and a protruding valve button in the center of the end, and a nozzle defined by radial projection of said end with a jet in the nozzle, said bomb having an end lip; which comprises a deformable disc having depending flanges adapted frictionally to engage over the lip to permit manual twisting of the cap, an opening in the disc through which the jet can emit spray, the disc adapted to be pressed in its center to engage against and depress the valve button, the opening adapted to be aligned with the spray jet, and means preventing the center of the disc from being pressed against the button unless the opening is aligned with said jet.
- 20 4. In combination with an aerosol bomb of the character described and having a lip on one end thereof, a valve housing in the end and substantially below the lip, a nozzle on the valve housing having a spray jet and a valve button on the top of the housing, a cap of deformable material frictionally engaged over said lip and adapted to rotate on said end by manual twisting, an opening in the cap adapted to be aligned with the nozzle so that when the center of the cap is pressed and deformed it will engage the button and release spray through the jet and out of the opening of the cap and means on the underside of said cap preventing the center of the

cap from being pressed against the button unless the opening is aligned with said jet.

5. In combination with an aerosol bomb of the character described and having a lip on one end thereof, a valve housing in the end and substantially below the lip, a nozzle on the valve housing having a spray jet, and a valve button on the top of the housing, a cap of deformable material frictionally engaged over said lip and adapted to rotate on said end by manual twisting, an opening in the cap adapted to be aligned with the nozzle so that when the center of the cap is pressed and deformed it will engage the button and release spray through the jet and out of the opening of the cap, said cap being provided with a projection adapted to ride upon said nozzle during all positions of the cap but one, said last mentioned position being that of proper alignment of the opening with the jet.

6. In combination with an aerosol bomb of the character described and having a lip on one end thereof, a valve housing in the end and substantially below the lip, a nozzle on the valve housing having a spray jet, and a valve button on the top of the housing, a cap of deformable material frictionally engaged over said lip and adapted to rotate on said end by manual twisting, an opening in the cap adapted to be aligned with the nozzle so that when the center of the cap is pressed and deformed it will engage the button and release spray through the jet and out of the opening of the cap, said cap being provided with a projection adapted to ride upon said nozzle during all positions of the cap but one, said last mentioned position being that of proper alignment of the opening with the jet, said projection being in the form of an annular depending ridge having a discontinuity, the diameter of the valve housing being less than that of the

ridge and concentrically aligned therewith, and the nozzle extending beyond the circumference of the valve housing and into the path of the ridge, whereby said cap cannot be depressed unless the nozzle is positioned at the said discontinuity.

7. The combination of a cap for an aerosol bomb having a lip on one end thereof, a central valve housing in said end provided with an outwardly facing annular surface and a radially outwardly projecting extension of said surface defining a nozzle having a jet therein, and a valve button protruding from the center of said annular surface, said cap comprising a deformable disc member closing off said end and having a flange means adapted frictionally to engage over the said lip, an opening in the cap adapted to be aligned with the jet, the center of the disc member adapted to be pressed against the button to operate said bomb, and means preventing the center of the disc from being pressed against the button unless the said opening is aligned with the jet, comprising a C-shaped ridge in the bottom of the disc concentrically arranged relative to the annular surface but being larger than same, said extension adapted to engage said ridge except at the discontinuity thereof.
